HEAT TRANSFER IN DENTURE MOLDS

Francis Taub, Brooklyn, N. Y.

Application August 6, 1941, Serial No. 405,691

9 Claims. (Cl. 18—34.1)

In the molding of dentures it has been customary to apply heat to the external surface of the flask, the heat being transmitted by conduction through the metal to the refractory or plaster mold and therethrough to the denture material.

It has been found that the applied heat first reaches the outer surfaces of the denture and that it takes about thirty minutes before the heat travels inwardly until the temperature is uniform all through the denture.

Thermosetting denture materials such as those made of acrylic resin contain certain gases which escape during the time the material is subjected to heat.

When the heat is applied from the exterior of the flask containing the mold, the outer part of the denture sets first and traps the escaping gases in the inner portion of the mold and denture, thereby causing porosity in the molded denture. When the heat is applied from the exterior of the flask, the outer part of the denture which is the thickest, sets before the inner and thinner portion and the uneven setting causes warpage of the denture.

In cooling the hot molded denture it has been customary to cool from the outside of the flask, thus causing the outer surface of the denture to cool prior to the cooling of the interior portion thereof. This unevenly distributed cooling causes uneven shrinkage of the denture and warping and broken teeth.

I have found in actual practice that when the heat is applied first to the interior of the mold, that the gases will be free to escape outwardly and no porosity or warpage will result. I have also found that when the cooling is applied first to the interior of the mold that shrinkage is lessened and also uniform and the cured denture assumes the shape of the mold more accurately and without breaking the teeth.

An object of this invention is to provide means for curing molded thermo-setting dentures by applying a heating medium and then a cooling medium to the inner portion of the mold and denture and without being solely dependent on heat transference from the external surface of the flask.

Another object of this invention is to provide means for heating and cooling thermoplastic dentures to be molded by applying a heating medium and then a cooling medium to the inner portion of the mold and denture being molded.

Another object of this invention resides specifically in providing a hollow chamber inside

the central portion of the plaster mold and means for circulating a hot liquid into and out of the said chamber for heating, and for circulating cold liquid into and out of the chamber for cooling the mold and denture.

Another object of this invention is to provide a thermo transferring hollow member designed for insertion into the said hollow chamber and preferably made of metal so as to be strong enough to withstand the molding pressure, and the said hollow member having openings in one wall thereof for introducing a heating or cooling medium thereinto.

Another object of this invention is to provide 15 passageways through a wall of the flask and through the plaster and in alignment with the openings in the thermo transferring hollow member so as to form passageways from the exterior of the flask to the interior of said hollow member.

Another object of this invention is to provide 20 a compact denture curing device whereby a denture may be simultaneously heated internally and externally and with the same liquid.

Another object of this invention is to provide 25 a thermo transferring hollow member having spring means for compensating for shrinkage of material at time of curing the dentures.

This application is a continuation in part of 30 my application Serial No. 275,090, filed May 22, 1939.

With the above and other objects in view, the 35 invention will be hereinafter more particularly described, and the combination and arrangement of parts will be shown in the accompanying drawings and pointed out in the claims which form part of this specification.

Reference will now be had to the drawings, 40 wherein like numerals of reference designate corresponding parts throughout the several views, in which:

Figure 1 is a top plan view of the mold, the top cover being removed and the mold being partly broken away to show a cross-sectional view of a thermo transferring device.

Figure 2 is a cross-sectional view, the section being taken as on line 2—2 in Figure 1.

Figure 3 is a cross-sectional view of the fluid circulating member.

Figure 4 is a front elevation of an assembled 50 dental flask, having the fluid circulating member connected to the city pressure water supply line, or other source of fluid.

Figure 5 is a view of a modified top cover for the dental flask with the fluid circulating member having tubes for fluid passing therethrough.

Figure 6 is a top view of the modified cover shown in Figure 5.

Figure 7 is a plan view of a modified heat transferring hollow member having two tubes in angular relation.

Figure 8 is a front elevation of a modified dental flask having circulating tubes spaced apart for use in a denture flask compressing device.

Figure 9 is a cross-sectional view of the flask shown in Figure 8, the section being similar to that shown in Figure 2.

Figure 10 is a plan view of a modified circulating member having circulating tubes spaced apart for use in a denture flask compressing device.

Figure 11 is a cross-sectional view of a pot for heating a fluid and an assembled denture flask compressing means mounted on an inverted receptacle in said pot, the receptacle having a riser tube forming a passage for carrying heated fluid to and through a thermo transferring hollow member in a denture mold, the pot being heated by any suitable means such as an electric stove.

Figure 12 is a side view of a modified thermo transferring hollow member having depressions in its outer walls and having spring means serving to automatically compensate for shrinkage of material at time of curing the dentures.

Figure 13 is an end view of the compensating member shown in Figure 12.

In the illustrated embodiment of the invention the numeral 10 indicates a dental flask made of metal and comprising a lower portion 11, an upper portion 12 and a removable top plate 13.

The flask 10 contains mold sections 14, 14' preferably made of plaster, and a molded denture 15 made from thermo-setting material. As is well known in the art, the molding is done in a press whereby pressure is exerted upon the charged flask to compress the denture material to the required form of denture, ready for the curing process.

For the purpose of curing the molded denture I have provided a thermo transferring hollow member 16 having therein a chamber or reservoir 17 and a threaded opening 18 in one of its walls. The member 16 is positioned above the central portion 19 of the molded denture 15 and is imbedded in the upper portion 14' of the mold.

The upper portion 12 of the flask 10 has an opening 20 extending through the plaster and in alignment with the opening 18. A fluid circulating member 21 having a threaded tubular body 22 has been secured in threaded engagement with the hollow member 16. The tubular member 22 passes through the opening 20.

The fluid circulating member 21, best shown in cross-section in Figure 3, comprises the tubular body 22 having an integral angular tubular extension 23, and an inner tubular member 24 having an integral angular extension 25.

As best shown in Figure 1, it will be readily seen that the volume of the chamber 17 is considerably larger than the passage through the fluid circulating member 21 and that this provides a relatively large body of heat transferring fluid constantly in storage inside the mold.

As shown in Figure 4, a flexible hose 26 is connected to the tubular extension 25. The hose 26 may be connected to the city water supply to cause water under pressure to enter the chamber 17 through the tubular member 24, the member 24 being elongated to cause the water to travel from the opening 18 to the far end of the cham-

ber 17. The water flows out from the chamber 17 through the tubular body 22 which terminates at the entrance to the said chamber and forms a duct 27 in circumscribing relation with a portion of the elongated tube 24. In the embodiment shown in Figures 1 to 4 inclusive, the outflowing fluid travels in a direction opposite to the flow of the incoming fluid and discharges through the extension 23 and through a hose 28.

Figures 5 and 6 show a modified cover plate 30 having two tubes 32 and 33 communicating with the chamber 34 in the fluid circulating portion 31. The tubes 32 and 33 are positioned at opposite ends of the chamber 34 and can be used for circulating a fluid therethrough for imparting heat thereto or for carrying away heat therefrom and from a denture in the mold.

Figure 7 shows a modified thermo transferring hollow member 35 having an elongated tube 36 for delivering fluid into said member and having a tube 37 threaded into the front wall 38 for discharging the fluid from the member 35. The tubes 36 and 37 are in angular relation to each other. This angular arrangement of the tubes provides an independent inlet and an independent outlet.

It is to be noted that the devices herein disclosed serve to cause the heat to travel from the central portion of the denture to the peripheral portion of the denture. The curing of the denture begins at the central and thinner portion thereof and continues to the peripheral and thicker portion. This inside-out heat transmission permits the gases generated during the curing process to escape freely from the molded denture through the peripheral portion of the denture and through the peripheral portion of the junction of the upper and lower wall sections. This provision for the escape of the gases makes it possible to mold and cure dentures without any porosity.

The inside-out heat transmission also causes the curing and setting to commence at the thinner central part of the denture prior to the curing and setting of the thicker part. The thicker outer part of the denture requires more time for proper setting than the thinner central portion. This inside-out heat transmission serves to prolong the time during which the setting of the thicker portion takes place and thus preventing warpage of the denture. In practice, when the interior of the mold is heated for about thirty minutes the entire mold may be immersed in a container of hot water at the proper curing temperature to bring the temperature of the exterior up to the temperature of the interior of the mold and thereby speeding up the curing operation and reducing the time of curing.

When a cold fluid is circulated into and out of the thermo transferring hollow member 16 while the denture is still hot and plastic, the inside cools and hardens and shrinks prior to the cooling and hardening and shrinking of the outer portion of the denture and permitting the outer portion to mold itself around the necks of the teeth without exerting excessive pressure against the teeth when the shrinkage of the inner portion takes place. Excessive shrinkage around the teeth is thereby prevented and this prevents breakage of the teeth.

It is to be noted that the method of operation herein disclosed provides for an inside-out heating and inside-out cooling from a central fractional portion of the mold outwardly towards the exterior of the mold.

By "inside-out heating" is meant that the heat

is transmitted to the central portion of the mold, that is, to the hollow chamber formed therein without the heating medium coming in contact with the outer metal flask.

By "inside-out cooling" is meant that the heat is removed from the central portion of the mold, that is, from the chamber formed therein and without the cooling medium coming in contact with the outer metal flask.

Referring to Figure 8, the numeral 40 indicates a modified dental flask similar to the flask 10, but having two openings 41 in the upper portion 42 and leading to the interior thereof. One of the openings 41 allows passage into the flask for a tube 43 for delivering fluid into a modified thermo transferring hollow member 45 shown in Figure 10. A tube 47 serves for discharging fluid from the member 45.

Figure 9 shows the flask 40 in cross-section, similar to Figure 2, but showing apertures 48 for inlet and outlet tubes positioned in considerably spaced-apart relation.

Figure 10 is a plan view of the modified thermo transferring hollow member 45, showing the circulating tubes 43, 47 frictionally inserted therein.

As shown in Figure 11, I have provided a denture curing device 50 whereby a denture may be simultaneously heated internally and externally and with the same source of fluid. The device 50 comprises a pot 51 containing a liquid 52 and mounted on a stove 53. An inverted receptacle 54 is on the bottom of the pot. A denture flask compressing means 55 is mounted on the receptacle 54. The receptacle 54 has a riser tube 56 and a rubber tube 57 connected thereto. The upper end of the rubber tube 57 is connected to the circulating tube 43 passing through an opening 41 in the flask 40. The tube 43 delivers fluid into the member 45, shown in Figure 10. The tube 47 serves for carrying the fluid discharged from the member 45 and leads back into the fluid 52 in the pot.

It is to be noted that the inverted receptacle 54 has an aperture 60 in its lower surface to allow passage thereto for the fluid 52. The receptacle 54 is a steam or vapor collector which forces steam or hot liquid through the hollow member 45 by convection currents. It is also to be noted that due to the momentary pressure developed in the receptacle 54, the hotter fluid is forced up and heats the member 45 and the denture 15 before the flask is heated from the outside. The outlet tube 47 discharging hot fluid into the pot 51 begins to heat the flask from the exterior and the denture is thereafter heated simultaneously internally and externally.

Figure 12 is a side view of a modified thermo transferring hollow member 65 having spring means for automatically compensating for shrinkage of the denture material during curing. As shown, the outer end walls 66 and 67 of the member 65 have elongated depressions 68, 69 serving to receive a bifurcated plate 70 in slidable engagement therewith. A spring 71 is disposed between the flat wall 72 of the member 65 and the plate 70. The spring 71 is of arcuate form and serves to space the plate 70 from the wall 72. Under operating conditions the spring is compressed by excess denture material, and when the molded denture material starts shrinking, the spring 71 automatically compensates for the shrinking of the material and keeps it under pressure. As shown in Figure 13, the plate 70 has clearance openings 73, 73 for the circulating tubes 43, 47 shown in Figures 8 and 10.

It is to be noted that when thick dentures are to be treated, a very small quantity of liquid is placed in the pot so as to only cover the receptacle 54 for internal heating, the liquid not coming into contact with the flask. After a predetermined time of internal heating, the pot is filled as shown in Figure 11, when the curing will commence externally of the flask.

In accordance with the patent statutes I have described and illustrated the preferred embodiments of my invention, but it will be understood that various changes and modifications can be made therein without departing from the spirit of the invention as defined by the appended claims.

I claim:

1. In combination with a dental flask having upper and lower plaster mold sections for curing dentures, said mold sections being formed to provide a cavity between them for denture material, a hollow metallic member imbedded in one of said mold sections, said hollow member having passage means connected therewith and leading exteriorly of said flask, and means for circulating a fluid into and out of said passage means and said hollow member for imparting a predetermined temperature to said denture material.

2. In combination with a dental flask having upper and lower sections, a hollow metallic member in one of said sections, said hollow member having passage means connected therewith and leading exteriorly of said flask, and means for circulating a fluid into and out of said passage means and said hollow member.

3. In a sectional dental mold adapted for molding and curing dentures by imparting a pre-determined temperature to the interior of the mold, a hollow metallic member in one of said sections, said hollow member having passage means connected therewith, said mold having opening means and said passage means passing through said opening means, and leading exteriorly of said mold, and means for circulating a fluid into and out of said passage means and said hollow member.

4. In a denture mold designed for imparting a pre-determined temperature to the interior thereof, a flask having upper and lower plaster mold sections, a hollow metallic member in one of said sections, an outlet in said hollow member, said hollow member having passage means connected therewith and leading exteriorly of said flask, said passage means comprising an elongated tube mounted inside said outlet and extending to the far end thereof for delivering a fluid therein, said flask having an opening in alignment with said outlet, a tube secured in engagement with said outlet and in circumscribing relation with said elongated tube, said circumscribing tube terminating substantially at the inner face of said hollow member and serving for discharging said fluid from said hollow member.

5. A method for uniformly curing a molded denture in a metal flask having upper and lower plaster sections and having a hollow metallic member at the central portion of one of said plaster mold sections and at the central portion of said denture and without direct contact with the metal flask, which consists in circulating a hot fluid solely into and out of the interior of said hollow member until the interior of said mold reaches a pre-determined temperature, and then circulating a cold fluid solely into and out of the interior of said hollow member until said

mold and denture is cooled to room temperature.

6. A method for curing a thermo-setting denture material in a sectional mold made of plaster or refractory material to form unwarped and uniformly cured dentures, which consists in forming a chamber in the interior and central portion of one of the sections of said mold, in circulating a hot fluid into and out of said chamber, and simultaneously subjecting the whole exterior of said mold to a pre-determined curing temperature for said denture material.

7. A temperature imparting device for imparting a pre-determined temperature to the interior of a plaster or refractory material mold having upper and lower sections and an intermediate cavity for molding solid dentures, comprising a hollow reservoir member designed for imbedding in one of said mold sections, said hollow member being out of contact with said mold cavity, and means for heating the interior of said hollow reservoir member.

8. A temperature imparting device for imparting a pre-determined temperature to the interior of a plaster or refractory material mold having upper and lower sections and an intermediate

cavity for molding solid dentures, comprising a hollow reservoir member designed for imbedding in one of said mold sections, said hollow member being out of contact with said mold cavity, and means for circulating a fluid into and out of said hollow reservoir member.

9. In combination with a metallic flask having upper and lower mold sections defining a mold cavity therebetween, said mold sections being made of plaster for molding and curing dentures by imparting a predetermined temperature to the interior and exterior of the mold, a hollow metallic reservoir member completely embedded in one of said sections, said hollow reservoir member having passage means connected therewith, said one of said sections having opening means and said passage means passing through said opening means and leading exteriorly of said one of said sections, means for circulating a fluid into and out of said passage means and said hollow reservoir member, and means for simultaneously subjecting the exterior of said mold to a predetermined curing temperature for said denture material.

FRANCIS TAUB.
